MAGNETIC KNIFE HOLDER

Richard B. Cronheim, 411 N. 7th St., St. Louis, Mo.

Filed Feb. 3, 1961, Ser. No. 63,816

Term of patent 14 years

(Cl. D44—29)

FIG. 1

FIG. 2

FIG. 3

FIG. 4

FIG. 5

FIG. 6

FIG. 1 is a perspective view of a magnetic knife holder embodying my new design;

FIG. 2 is a top plan view thereof;

FIG. 3 is a side elevational view thereof;

FIG. 4 is a side elevational view of the right side thereof;

FIG. 5 is a bottom plan view thereof; and

FIG. 6 is an end elevational view thereof.

I claim:

The ornamental design for a magnetic knife holder, substantially as shown.
